UNITED STATES PATENT OFFICE.

JULIUS ZETTER, OF FREEBURG, ILLINOIS.

MORTISING-MACHINE.

984,057.

Specification of Letters Patent. Patented Feb. 14, 1911.

Application filed June 24, 1910. Serial No. 568,738.

To all whom it may concern:

Be it known that I, JULIUS ZETTER, a citizen of the United States, residing at Freeburg, in the county of St. Clair and State of Illinois, have invented certain new and useful Improvements in Mortising-Machines, of which the following is a specification, reference being had therein to the accompanying drawing.

This invention relates to an improvement in mortising machines, and more particularly to the type of mortising machines employing chain cutters.

The object of the present invention is the provision in a device of this character of such construction that mortises of any desired depth may be cut either entirely through or partially through timber of various thicknesses.

A further object of the invention is the provision in a device of this character of means for bodily adjusting the chain cutter so that it may be used with timber of various widths.

A further object of the invention is the provision of an improved gage in a machine of this character so as to insure the cutting of the mortise at the proper point.

Other objects of the invention will be apparent from the detailed description hereinafter when read in connection with the accompanying drawings forming a part hereof, wherein a convenient embodiment of the invention is illustrated and wherein like numerals of reference refer to similar parts in the several views.

In the drawings, Figure 1 is a side elevation of the mortising machine, Fig. 2 is a cross section on line 2-2 of Fig. 1, Fig. 3 is a section on line 3-3 of Fig. 1, and Figs. 4 and 5 are detail views showing the means utilized for limiting the downward movement of the cutter.

Referring now more particularly to the drawings, A designates the bed of the mortising machine, upon the upper surface of which are rigidly supported a pair of parallel bars B, B, between which is adapted to be supported the timber which is to be cut. Supported upon the bars B, B is a frame C in which is adjustably mounted the chain cutter, as will be hereinafter more particularly set forth. The frame C comprises parallel side walls, between which the chain cutter is adapted to be supported, and the lower ends of said walls are provided with

laterally disposed portions c which rest upon the upper surfaces of the parallel bars B, B. The laterally disposed portions c of the frame C are provided with transverse slots 60 c' therein, through which pass fastening bolts c² which engage the bars B, B and serve to clamp the frame C rigidly thereto. The slots c' permit the entire frame C and the cutter carried thereby to be adjusted laterally, and one of the laterally disposed portions c of the frame C is preferably provided with a suitable scale so that the operator may adjust the frame to any desired extent.

D designates the frame employed for supporting the chain cutter and such frame comprises parallel side bars d, d in the upper and lower ends of which are journaled sprocket wheels d', d', which serve to support the chain cutter d², which may be of any well known type. The width of the chain cutter d² exceeds that of the supporting frame d therefor, so that such frame will not interfere with the cutting action of the chain when cutting mortises. The frame D is positioned between the parallel side walls of the frame C and the side bars of the frame D are provided adjacent the upper portion thereof with bearing blocks d³ which project outwardly through longitudinal slots c³ formed in the side walls of the frame C, said bearing blocks being provided with slots in the sides thereof which engage the portions of the side walls of the frame C bounding the slots c³. Preferably two or more bearing blocks d³ are provided on each side of the cutter carrying frame D so that such frame will slide freely in the frame C and will be held against any canting or twisting during its movement in the frame C. The bearing blocks d³ are positioned adjacent the upper end of the cutter carrying frame D, thus leaving the entire lower end of said cutter frame free, which enables the cutting of mortises entirely through timbers of considerable thickness.

E designates a power shaft which is positioned at any suitable point above the bed A of the frame and is provided with a suitable drive pulley E' thereon. Pivotal 105 connected to the power shaft E at each side of the drive pulley E' and depending therefrom are a pair of links F, F, the lower ends of which are pivotally connected to a short shaft F'.

G, G designate a pair of links which are pivotally connected at one end to the shaft

F' outside of the links F, F. The other ends of the links G, G project between the side walls of the frame C and are pivotally connected to the shaft which supports the 5 upper sprocket wheel d' of the chain cutter.

Loosely mounted upon the shaft F' between the links F, F is an idle pulley F² and alongside of said idle pulley is a fast pulley F³. The shaft F' is also provided 10 outside of the links F, F with a fast pulley F⁴ which is adapted to be connected by a suitable belt with a pulley F⁵ which is fixedly secured to the shaft which supports the upper sprocket wheel d' of the chain cutter. 15 A belt F⁶ normally connects the drive pulley E' and the idle pulley F² and a suitable belt shifter is secured to one of the links F so that the operator may, when desired, shift the belt to the fast pulley F³, and thus 20 effect the driving of the chain cutter.

Carried by the chain cutter frame D and positioned outside of the walls of the frame C is a vertically disposed rack bar H, which meshes with a gear wheel H' which is positioned below a bearing plate H² secured to one of the side walls of the frame C. Meshing with the gear wheel H' is a pinion H³, the shaft of which projects without the bearing plate H² and has secured thereto 25 an operating handle H⁴. The operating handle H⁴ is provided with a spring pressed bolt h which normally extends into a segmental slot h' formed in the bearing plate H², and the operating handle is provided 30 with any suitable hand piece for retracting the bolt when it is desired to do so. 35

Underlying the segmental slot h' in the bearing plate H² is a plate which is pivotally supported upon the shaft of the pinion H³, which plate is provided with an aperture h³ which underlies the slot h' and is movable in the path thereof when the plate is shifted on its pivot. The outer edge of the plate h² is provided with a lip 40 h⁴ which is bent over so as to overlie the front face of the bearing plate H², the edge of the bearing plate which is engaged by said lip being formed on an arc of a circle, the center of which is the shaft of the pinion H³. Threaded in the lip h⁴ is a set 45 screw h⁵ which is adapted to engage the edge of the bearing plate H² to hold the plate h² against movement on its pivot. In feeding the cutter, the spring pressed bolt h of the operating handle H⁴ occupies a position 50 within the segmental slot h' in the bearing plate H', and the lower end thereof rests upon the plate h² which overlies said segmental slot. The handle may be turned 55 until the spring pressed bolt h thereof engages the aperture h³ in the plate h², when the handle will be locked against further movement and the feeding of the cutting chain stopped. As the plate h² may be 60 adjusted to bring the aperture therein at any 65

point of the segmental slot, it will be seen that the operator can set the machine so that the chain cutter can be fed downwardly to a predetermined extent and then stopped, so that the depth of the mortise which is to be 70 cut can be regulated to a nicety. In addition to the segmental slot h', the bearing plate H² is also provided with an aperture h⁶ therein which is also positioned in the path of movement of the spring pressed bolt 75 h of the operating handle. When the spring pressed bolt of the operating handle is in engagement with the aperture h⁶, the chain cutter is in its extreme uppermost position, and out of the way and the handle is moved to this position whenever it is desired to remove a finished piece of work or 80 insert a new piece of work.

Rigidly secured to the upper surface of the bars B, B at one side of the frame C is 85 a plate I, which is provided with a slot i therein which extends transversely of the machine. Slidably mounted upon the upper portion of the plate I is a rack bar I', the outer end of which projects downwardly 90 through the slot i in the plate I, and terminates in a presser foot i'. Rotatably supported upon the plate I and meshing with the rack bar I' is a pinion K.

K' designates an operating handle for 95 actuating the pinion and shifting the rack bar and such actuating handle is provided with a suitable detent h which is adapted to engage a segmental rack h', secured to the plate I, to hold the operating handle in various positions of adjustment. In practice, the rack bar is normally retracted and the timber which is to be mortised is advanced on the bed of the machine between the bars B, B until it has been properly positioned 100 with reference to the chain cutter. The actuating handle K' is then actuated until the timber is firmly held between the presser foot i' of the rack bar I' and the opposing bar B, and after the timber has been so secured 110 the mortise is then cut.

Positioned immediately below the plate I and journaled in suitable bearings secured to the under side of the bed A of the machine, is a shaft L upon which is secured a 115 toothed wheel L', the periphery of which projects for a slight distance through the bed of the machine. The shaft L is provided with a suitable handle to permit of its actuation. The toothed wheel L' is utilized 120 to facilitate the feeding of the timber to be mortised along the bed of the machine.

The bed A of the machine is provided with a plurality of openings a therein beyond the frame C into any one of which is 125 adapted to be fitted a stop gage a'. The stop gage is utilized where it is desired to mortise a large number of pieces of timber so that the mortises will be positioned the same distance from the ends of the pieces 130

of timber. In this case the stop gage is placed in the proper opening and each piece of timber is then fed into the machine until it abuts the stop gage when it is clamped in 5 a manner heretofore described and the mortise cut.

Pivottally secured upon the upper portion of one of the bars B at one side of the frame C is a gage M which is utilized in marking 10 the timber which is to be mortised so as to insure its being properly positioned beneath the chain cutter. The gage M comprises a portion *m* which is positioned transversely of the machine and the outer end of which 15 lies between the bars B, B and is provided with oppositely disposed sharpened marking portions, and a portion *m'* which extends from the inner end of the portion *m* in a direction parallel to the bars B, B and 20 is pivotally connected to one of the bars B in such a manner that the gage may be swung to cause the portions *m* thereof to lie upon either side of the pivotal point of the gage. The gage is so formed that when the 25 portion *m* thereof occupies the position nearest to the chain cutter, the distance between the portion *m* and the pivot of the gage is just one half the distance between the portion *m* and the center of the chain cutter. 30 With this construction, if it is desired to cut a mortise at any particular point in a piece of timber, such piece of timber is moved along the bed until the center of the mortise which is to be cut underlies the 35 marking point of the portion *m* of the gage. With the timber in this position, the gage is swung over to its opposite position and the other marking point thereof utilized to mark the timber. The gage is then returned 40 to its initial position and the timber is advanced along the bed of the machine until the mark last made thereon underlies the marking point of the gage. When the timber occupies this position, the mark which 45 has been made to indicate the center of the mortise will directly underlie the center of the chain cutter. Instead of the swinging gage thus described, it is obvious that in lieu thereof two fixed gages might be employed, in which case such gages would be 50 so positioned that the distance between the same would be equal to the distance between the gage nearest the chain cutter and the center of the chain cutter. 55 The bed of the machine is provided with a suitable opening therein directly beneath the chain cutter of a size large enough to permit the cutter to pass therein regardless of the position to which the frame C may be 60 adjusted.

While I have illustrated a convenient embodiment of the invention, it will be understood that many changes may be made to the form and construction therein shown 65 without departing from the spirit and scope

of the invention as defined in the appended claims.

I claim:

1. In a mortising machine, a bed, a frame supported over said bed, a chain cutter 70 slidably mounted in said frame, and means for feeding said cutter toward and away from the bed, said means including an actuating handle provided with a spring pressed detent, a plate having a segmental slot in 75 which the spring pressed detent of the actuating handle normally travels, a plate underlying the segmental slot in said first mentioned plate and provided with an opening therein adapted to receive the spring 80 pressed detent of the actuating handle, and means for adjusting said last mentioned plate.

2. In a mortising machine, a bed, a pair of parallel bars supported on said bed, an 85 upwardly extending frame supported on said bars, means for adjusting said frame laterally, a chain cutter slidably mounted in said frame, means for driving said cutter, means for feeding the cutter toward 90 and away from the bed, and an adjustable clamping bar arranged opposite the inner surface of one of the parallel bars on the bed.

3. In a mortising machine, a bed, a pair 95 of parallel bars supported on said bed, an upwardly extending frame provided at its lower end with laterally extending supporting portions adjustably mounted on said parallel bars, a chain cutter slidably mounted in said frame, means for driving the cutter, means for adjusting the cutter toward and away from said bed, and means for clamping the work between the parallel bars 100 on the bed beneath said chain cutter. 105

4. In a mortising machine, a bed, a chain cutter adjustably supported over said bed, a gage pivotally supported on the bed at one side of said chain cutter, the distance between the outer end of said gage and its 110 pivot point being equal to one half the distance between the outer ends of the gage and the center of the chain cutter.

5. In a mortising machine, a bed, a frame supported thereon, a vertically adjustable 115 cutter mounted in said frame, and means for feeding said cutter toward and away from the bed, said means including an actuating handle provided with a spring pressed detent, a plate provided with an opening therein lying in the path of the detent of the actuating handle, and means for adjusting said plate to limit the extent of movement of the actuating handle. 120

In testimony whereof I affix my signature 125 in presence of two witnesses.

JULIUS ZETTER.
